CLAIM

(**) Term: **14 Years**

The ornamental design for a calculator with perpetual calendar, as shown and described.

(21) Appl. No.: **29/123,390**

DESCRIPTION

(22) Filed: **May 18, 2000**

FIG. 1 is a perspective view of the calculator with perpetual calendar in a closed state showing the new design;

(51) LOC (7) Cl. **19-03**

FIG. 2 is a front view of the new design in a closed state;

(52) U.S. Cl. **D19/21; D19/25; D10/2;**

FIG. 3 is a rear view of the new design in a closed state;

(58) Field of Search **D18/2, 6, 7; D19/20,**

FIG. 4 is a left side view of the new design in a closed state;

D19/21, 25; D10/2, 3, 15, 18; D14/100-113;

FIG. 5 is a right view of the new design in a closed state;

434/304; 283/2; 40/107-122; 368/10, 11,

FIG. 6 is a top view of the new design in a closed state;

12, 21, 28-30, 46, 276-285, 82-84, 239-242;

FIG. 7 is a bottom view of the new design in a closed state;

235/61 R

FIG. 8 is a perspective view of the new design in an opened state;

(56) **References Cited**

FIG. 9 is a front view of the new design in an opened state;
